UNITED STATES PATENT OFFICE.

NOAH J. BECKNER, OF SEATTLE, WASHINGTON, ASSIGNOR TO PROGRESSIVE
COMMODITY COMPANY, OF SEATTLE, WASHINGTON, A CORPORATION OF
WASHINGTON.

SWITCH-STAND LOCK.

1,384,505.

Specification of Letters Patent. Patented July 12, 1921.

Application filed November 27, 1920. Serial No. 426,840.

To all whom it may concern:

Be it known that I, NOAH J. BECKNER, a citizen of the United States, residing at Seattle, in the county of King and State of Washington, have invented certain new and useful Improvements in Switch-Stand Locks, of which the following is a specification, reference being had to the accompanying drawings.

10 This invention relates to switch stands, and particularly to locks for locking the operating lever of the switch stand in a depressed or depending position, thus preventing the switch from being thrown until the 15 lever or handle is unlocked and raised to its operative or horizontal position.

The general purpose of my invention is to provide a lock for the levers or handles of switch stands which is shifted to an un- 20 locked position by a key, which is further so constructed that the key cannot be withdrawn until the lever has been again turned to a vertical position, and which has a cover or shield for the keyhole normally disposed 25 over the keyhole.

More particularly, one object of my invention is to provide a switch stand lock wherein the lever is prevented from being shifted to its horizontal or operative position to shift the switch by an obstruction 30 within the lock casing and acting to block the movement of the lever, and provide key operated means whereby this obstruction may be removed from behind the lever and 35 permit the lever to be shifted.

A further object is to provide a construction of this kind in which the parts of the lock are held in their locking position by a detaining device, this detaining device being partly shifted from its operative position by a shifting movement given to the keyhole shield, the rotation of the key within the lock acting to further lift this detaining device and then acting to cause an 40 operative engagement to be secured between the key and the lever obstructing member to swing this lever obstructing member out of its obstructing position.

And a further object is to provide a lock 50 of this character with a gravity actuated detaining mechanism, thus doing away with the necessity of using springs, these springs

being relatively costly, difficult to secure of exactly the proper tension, liable to break when subjected to intense cold or variations of temperature, and thus securing a greater life for the lock than is commonly the case.

A still further object is to provide a lock of this character with very few working parts, these parts being entirely housed and protected from the elements under all climatic conditions, the lock being constructed so that it may be applied to practically all makes of switch stands, and being further so constructed that the key cannot be removed from the lock until the lock is positively shifted to its fully operative or locking position.

Another object is to provide a lock of this character wherein the lever is prevented from being shifted when the lock is in its locking position by a heavy ring forming a block and seating against a suitable abutment on the lock casing and disposed between said abutment and the lever, and provide key actuated means whereby this ring may be shifted to a raised position out of the way of the lever and permitting the lever to be shifted to its operative position without obstruction.

Another and most important object of this invention is to so mount the ring or obstructing member upon the key actuated means supporting it that this obstructing member is entirely free to have a slight independent movement upon the key actuated support so that any shock or jar against the obstructing member caused, for instance, by a sudden attempt to lift the switch operating lever to its operative position will not be transmitted to the key actuated mechanism but will be borne solely by the obstructing member, thus preventing any strain being put upon the journal post on which the key rotates and preventing this journal post from being broken off or bent.

And another object is to provide a locking device holding the obstructing member from being lifted or shifted out of its operative or obstructing position, which locking device comprises a pivoted weight which must be lifted by an actuation of the key actuated mechanism, and in this connection to provide means whereby the weight may be

partially lifted comprising a shield plate pivoted to the outer casing of the lock and normally urged by the weight over the key-hole, which shield plate must be shifted by 5 the key before the key can be inserted in the keyhole and which thus acts to partially raise the weight, the weight being raised entirely from its locking position by the initial rotation of the key actuated mechanism under the action of the key, this weight not only acting as a lock normally preventing any actuation of the key actuated mechanism without the use of the key, but also acting as the means for closing the shield 10 over the keyhole to thus prevent the entrance of moisture into the interior of the lock.

Other objects will appear in the course of the following description.

20 My invention is illustrated in the accompanying drawings, wherein:—

Figure 1 is a vertical sectional view of the upper portion of a conventional switch stand showing my lock applied thereto;

25 Fig. 2 is a fragmentary elevation of a portion of the switch stand showing the lock casing in elevation;

Fig. 3 is a vertical section on the line 3—3 of Fig. 2;

30 Fig. 4 is a section on the line 4—4 of Fig. 3;

Fig. 5 is a like view to Fig. 4, but showing the parts in their unlocked position;

Fig. 6 is a perspective view of the key;

35 Fig. 7 is a perspective view of the key-hole shield;

Fig. 8 is a perspective view of the carrier for the locking ring;

Fig. 9 is a perspective view of the key 40 actuated device for shifting the carrier;

Fig. 10 is a perspective view of the weight;

Fig. 11 is a fragmentary face view on a large scale of the locking mechanism.

Referring to Fig. 1, it will be seen that 45 I have illustrated my invention as applied to a switch stand of a usual type having a table 10, upon which is mounted the usual blockhead 11 which engages with the mast or vertical shaft 12 of the switch stand.

50 The table is notched at, say two points, as at 13, in the usual manner, and the blockhead is bifurcated at one end or otherwise formed to receive between it the lever 14 which is pivoted to said blockhead by the pivot bolt or

55 like pivot element 15. The upper end of this lever is angularly bent with relation to the body of the lever, as at 16, and is commonly perforated adjacent its extremity for the insertion of a padlock. Ordinarily means

60 is provided on the switch stand itself whereby a padlocked staple or bolt may engage this perforation. When this lever 14 is turned to a horizontal position it disengages from the notches 13 of the table 10 and then

65 the blockhead 11 may be oscillated over the

face of the table to oscillate the mast or shaft 12 in the usual manner. So far I have described a construction which is commonly found in almost all switch stands in use today on railroads.

70

The locking mechanism which I have devised is disposed entirely within a housing 17 which is, of course, of metal, this housing having a relatively wide lower portion to receive upwardly extending lugs 18

75

formed upon the blockhead 11. The housing is held to these lugs by means of cap bolts 19 and the outer faces of the opposite walls of the housing are formed to provide sockets 20 within which the heads of these

80

cap bolts are disposed when the cap bolts have been turned home. Thus the housing is firmly and securely held upon the blockhead.

85

One wall 21 of the housing extends straight upward, while the opposite wall extends upward, as at 22, for a certain distance, then extends inward, and then extends upward, as at 23. The top of the housing extends laterally from this wall 23,

90

then downward, as at 24, then laterally, as at 25, to join with the upper end of the wall 21. The wall 23 of the housing is thickened, as at 26, and extending through this thickened portion and pinned thereto is an arbor or spindle 27.

95

This spindle 27 is reduced in diameter, at 28, and is further reduced in diameter, as at 29, this reduced portion 29 extending out through a keyhole 30 in the wall 21 of the housing. This reduced portion 29 is to provide a center upon

100

which the lock operating key may be disposed and rotated. This keyhole 30 is normally covered by a keyhole shield 31 disposed upon the outer face of the wall 21 and pivoted upon a pivot pin, bolt, stud, or

105

like element 32. This plate or shield 31, as illustrated in Fig. 7, is approximately segmental in form, and that edge of the plate remote from the pivotal center there-

110

of is formed to provide an outwardly projecting flange 33, this flange and the adjacent edge face of the plate conforming in shape to the shape of the keyhole and the shape of the key. This flange extends to a boss 34 formed at one corner of the plate,

115

and from this boss extends inward a pin 35. This pin 35 extends through a slot 36 formed in the face plate or wall 21.

Projecting inward from the wall 21 is a stud, bolt or like device 37, upon which is mounted a detaining or locking weight, illustrated in detail in Fig. 10. This weight is, generally speaking, curved or angular in form and is formed at its free end to provide a nose 39 which normally, and when

120

the weight is depressed, engages over the pin 35 so that if the shield 31 is oscillated upon its pivot from the dotted line position in Fig. 2 to the full line position in this figure, the pin 35 will, bearing against the

125

130

nose 39, act to lift the free end of the weight from the position shown in Fig. 4 to the position shown in Fig. 5.

This gravity actuated detent or pivoted weight 38 is formed adjacent its hinged end with a laterally projecting detent face 40. It will be noted that the tongue 39 is disposed to one side of the medial plane of the weighted detent 38 and that this detent face 40 is disposed to the other side of this medial plane. The inner face of that portion of the weight between the body of the weight and the pivotal axis thereof is slightly concave, as at 41, the concavity being formed on a relatively short curve, and the inner face of the weight is concavely curved, as at 42.

Mounted upon the portion 28 of the spindle and bearing against the shoulder at the end of this reduced portion 28 is a sleeve 43, which sleeve at one end carries a radially projecting arm 44 having a laterally projecting, somewhat elliptical and elongated head 45. This sleeve 43 at its opposite end from the arm 44 is provided with a segmental head 46, one face 47 of which is approximately radially disposed and is adapted to coact with the detent face 40 of the weight 38. The opposite end of the head 46 from the face 47 is formed with an upwardly extending arcuate lug 48.

Also disposed upon the portion 28 of the spindle 27 and mounted for rotation there-around is a member 49 formed with a radially projecting arm 50 carrying an arcuately extending horn or arm 51. The inner face of this arm is approximately concentric to the center of rotation of the member 49 but the outer face of the arm is eccentric thereto. Thus the outside face of this arm 51 at the rear or free extremity of this arm is nearer to the center of motion of member 44 than is the butt end of the arm. This butt end portion of the arm has its side face rounded, as at 52. Also projecting from the hub or member 49 is a radial portion 53 carrying an outwardly projecting lug 54 which is disposed in a plane inward of the plane of the arm 51. As illustrated in Fig. 5, the arcuate lug 48 of the head 46 projects toward the front wall 21 of the casing and into the path of movement of the lug 54, but the arm 51 moves in a path of movement outward of the end of the arcuate lug 48. The extremity of this arm 51 is adapted to be engaged by the bit of the key whereby the switch lock is operated. This key is designated 55, and the key has a tubular barrel to receive and rotate upon the reduced extremity of the spindle 27 and a bit 56 adapted to engage the extremity of the arm 51.

Carried upon the laterally projecting elliptical head 45 is a relatively heavy ring 57, and when the arm 44 extends downward and the lock is in its locked position, this ring 57

bears against an abutment lug 58 projecting inward from the rear end wall of the housing, this abutment lug being formed with a slightly concave outer face conforming to the curvature of the ring. The ring thus seats 70 against the outer face of this lug. Any upward movement of the ring is prevented because of the fact that the upper part of the ring touches against the relatively large portion of the spindle or post 27 where it 75 crosses the plane of movement of the ring 57. This ring or obstructing element, when it is in its lowered position, has its lowermost portion lying immediately above the upper end of the switch operating lever 14, that is 80 immediately above the angular portion 16 of the switch operating lever and, therefore, it will be obvious from Fig. 4 that if an effort is made to turn the switch operating lever from its depending vertical position to its 85 horizontal position to clear it from the notches 13 in the switch stand, the angular portion of the lever will strike against the obstructing ring 57, and the further movement of the lever will be blocked and that 90 the lever cannot be shifted to its horizontal and operative position until this ring has been moved out of the way. This ring is carried out of the way by the arm 44 with its head 45, which head projects into the ring, 95 as before stated, and supports it, and this oscillation of the arm 44 to carry the ring into the position shown in full lines in Fig. 5 is accomplished by turning the key, as will hereinafter appear.

In Figs. 5 and 11, it will be seen that the elliptical head 45 has a length less than the internal diameter of the annular obstructing member 57 so that the obstructing member has a certain amount of play within the ring 100 and the annular obstructing member in the position shown in Fig. 4 can be shifted toward the abutment 58 without bearing against or in any way affecting the locking mechanism. This is a very important feature of my invention, and my reason for making this annular member 57 loose upon the head 45 and larger than this head 45 and, therefore, independently movable within limits relative to the head 45 and to the arm 105 44 is that when the lock is in its locked position, as shown in Fig. 4, the annular member lies idle upon the head 45 and against the lug or abutment 58. Now in case the switch lever 14 was pulled or jerked under great 110 force and projected against the obstructing member 57, there will be no other part of the lock which could possibly have any strain or tension of any nature whatsoever thrown upon it, but the lever 14 would contact with 115 the obstructing member at one side, while the other side of the obstructing member abutted against the lug or abutment 58. Therefore, the lever, the ring, and the abutment member would be the only parts put into action 120 125 130

and no other part of the lock would have any strain thrown upon it. If this obstructing member 57 was rigidly carried by the arm 44 and the head 45, then if the operating lever was forced upward, the thrust would be carried to the journal post 28 instead of borne entirely by the obstructing member 57 and the lug 58, and this would cause the lock to break down or soon get out of working order by causing the journal post to break off and the whole lock would be out of commission. Furthermore, by making the member 57 annular, it can at all times be depended upon to operate properly. 10
15 No matter in what position it falls, it is always in operative position with relation to the lug or abutment 58 and the lever 14.

It is particularly pointed out that in this construction the key cannot be removed until 20 the lever 14 has been returned to its vertical position. The bit of the key is inserted between the lug 54 and the arm 51. As a consequence, the key has positive engagement with the member 53 which actuates the member 43. Therefore, if the key is backed up 25 to remove it, the bit of the key must engage the lug 54 and must turn this part 49 and thus must turn the arm 44 and lower the obstructing member, and if the lever 14 is in a 30 horizontal position and the angular end 16 thereof in the position shown in Fig. 5, it is obvious that the obstructing member cannot return to its normal position, that is the position shown in Fig. 4, and hence the key 35 cannot be turned to a position where it can be withdrawn. It is only when the lever 14 has been shifted back to the position shown in Fig. 4 that the obstructing member can be rotated from the position shown in Fig. 5 40 to that shown in Fig. 4 and the key withdrawn, and it will be further seen that when the key is withdrawn the weight 38 drops to the position shown in Fig. 4 and locks the 45 cover 31 over the keyhole. This action is very simple and yet very positive and is accomplished without the aid of a spring of any nature. The parts, as will be seen, are very few and require but very little machine 50 work to manufacture. Inasmuch as there is practically no strain on any of the parts except the obstructing member 57 itself and the abutment 58, it is obvious that it cannot readily get out of order and will last almost 55 indefinitely.

Attention is called to the fact that when the keyhole guard or shield 31 is shifted to insert the key, it lifts the weight 38 to the position shown in Fig. 11 but at this time the 60 shoulder 40 is still in engagement with the shoulder 47 of the part 43 and the parts are still locked. Upon a rotation of the key, however, the shoulder 52 and the curved outer face of the part 51 act to lift the 65 weight 38 entirely from behind the locking

mechanism. It is also to be noted that both of the parts 49 and 43 with its head 46 are necessary in order to cause the lock to properly function. If the lock were operated by an engagement of the key directly 70 with the member 43 and retained the weight to perform the duty of causing the closing of the keyhole shield 31, it would be impossible to lift the shield to a position where it uncovered the keyhole without completely 75 unlocking the member 47 from the weight at point 40. By providing the part 49, however, and so forming it that it lifts the weight prior to engaging the part 43, I have provided means to initially unlock the 80 engaging shoulders 47 and 40 which the keyhole cover shield fails to do. It is obvious that if this part 49 were not provided that a complete release of all locking parts would be secured by simply lifting the keyhole 85 cover shield. This, however, is obviated by the construction which I have provided. Attention is called to the fact that the weight 38 performs a number of functions. It 90 causes the shield to cover the keyhole when the lock is in locked position and this without the necessity of using a spring. Thus the cover shield is held in its closed position much more strongly than is possible with a spring, as springs tend to weaken and to 95 break. Furthermore, the weight 38 forms a latch inasmuch as its shoulder 40 engages with the shoulder 47 and thus latches the member 43 from any movement until member 49 is rotated to completely release the 100 weight. Furthermore, the weight 38 keeps the member 49 in such position that the lugs 51 and 54 will be disposed on opposite sides of the keyhole so that when the key is inserted to unlock the lock, these lugs 51 and 105 54 will always be in the proper position for engagement with the bit of the key. The weight of the obstructing member 47 would, of course, form a lock for the switch stand lever, but if the weight 38 was eliminated 110 there would be nothing to lock the obstructing member in its lowered position and only the obstructing member 57 could be depended on. By providing the weight 38, however, the obstructing member is securely 115 locked in its lowered position until operated by the proper key. It will be obvious that the weight would be necessary to the apparatus without the mechanism even though the shield 31 were omitted, but inasmuch as 120 in switch locks a shield for the keyhole opening is a standard requirement, such a shield is provided and urged to its locked position by the weight 38, this shield acting to relieve the key of the duty which it would otherwise have to perform of entirely lifting the 125 weight because as the shield is shifted for the insertion of the key, it partially lifts the weight and the key has only to move a relatively small distance before the weight is en- 130

tirely lifted to completely free the locking mechanism.

It will be seen from Fig. 4 that the angular end 16 of the lever projects out beyond the main body of the housing and that this main body of the housing is provided with an outwardly projecting hood 59 which extends outward and downward from the front end face of the housing. It will thus be seen that all the parts of the lock and of the lever itself are fully protected against rain, sleet, ice, etc.

The general operation of this locking mechanism will be obvious from what has gone before. Assuming that the lever 14 is in its depressed or dependent position with the angular end 16 extending in a horizontal position and that thus the switch lever with the blockhead 11 are locked from rotative movement in a horizontal plane, then at this time the lever is held from any unlocking movement by the ring 57, which seating as it does against the post or spindle 27 at one point and against the abutment 58 at another point, completely blocks the upward and inward movement of the angular end of the lever. The lever 14 may move a slight distance, but only a slight distance and not enough to carry it out of the notch 13. At this time the member 46 or head on the tubular shaft 43 is held from any rotation accidentally or otherwise by the detent shoulder 40 of the weight 38 which bears against the detent face 47 of the head 46. Therefore, it is impossible to turn the tubular shaft 43, the arm 44 and the ring 57. The nose 39 of weight 38 bears against the pin 35 and holds the shield 31 closed over the keyhole.

Now when it is desired to unlock the lock, the key 55 is used to force the guard or shield 31 laterally until the keyhole is disclosed. This lateral movement of this shield or guard 31 acts to lift the weight 38 a certain distance, but while the two faces 14 and 47 move toward a position of disengagement they do not entirely disengage at this point. If now the key be rotated in a counter-clockwise direction, the bit 56 will engage the end of the arcuate arm 51 and a rotation of the member 50 will cause the lug 54 to move into engagement with one end of the lug 48. Just before the lug 54 comes into engagement with the end of the lug 48, the protuberant end 52 of arm 51 will engage the circular face 41 and this will act to lift the weight sufficiently to disengage the faces 40 and 47 so that when the lug 54 has engaged the lug 48, the faces 47 and 40 are disengaged from each other. Thus a continued movement of the key causes the rotation of the hollow shaft 43 and thus, through its arm 44, lifts the blocking ring 57 to its raised position, as indicated in full lines in Fig. 5, where it

is entirely out of the way of the angular end 16 of the lever 15. This permits the lever to be shifted to its horizontal or operative position and the switch to be turned. The key is prevented from being withdrawn from the lock until the arm 44 has been returned to its dependent position, and obviously this arm 44 cannot be returned to this dependent position until the weight has been turned to the position shown in Fig. 4, and this is not possible until the switch stand handle or lever has been turned to its dependent position. Thus the key cannot be withdrawn from the lock until the parts of the lock have been shifted to their locking position. Then and only then can the key be withdrawn. Of course, as soon as the key is turned in a counter-clockwise direction to return the parts to their original or locking position, the weight will tend to fall and will bear against the pin 35 and urge the shield plate 31 to its closed position, but it can only shift to this closed position when the key has been withdrawn from the lock.

I claim:—

1. The combination with an operating member movable into or out of an operative position, of means for preventing the movement of the member from its inoperative position including a rigid abutment disposed in spaced relation to the operating member when in its inoperative position, a key operated obstructing member movable into the space between the abutment and the operating member or out of such space, a weight operatively engaging said obstructing member and locking the obstructing member from movement out of its obstructing position, and key actuated means for lifting the weight out of its obstructing position.

2. The combination with an operating member movable into or out of an inoperative position, of means for preventing the movement of the member from its inoperative position including a rigid abutment disposed in spaced relation to the operating member, an obstructing member adapted to be disposed between the abutment and the operating member, and key operated means for shifting the obstructing member into or out of its obstructing position and upon which the obstructing member is loosely mounted for independent movement.

3. The combination with a switch stand having a notched table, and a swinging operating lever shiftable into or out of the notches, of means for locking the lever in its inoperative position comprising a key actuated oscillatable arm, an obstructing member carried by said arm and normally disposed in a locking position in the path of movement of the lever to an operative position, and an abutment with which said ob-

structing member engages when disposed in the path of movement of the lever, said obstructing member when shifted out of its obstructing position being shifted away from the abutment.

4. The combination with a switch stand having a notched table and a swinging operating lever shiftable into or out of the notches, an obstructing member movable into 10 position between the lever and said abutment and in the path of movement of the lever to its operative position and key actuated means for shifting said obstructing member out of its obstructing position and 15 away from the abutment.

5. The combination with a switch stand having a notched table and a swinging operating lever shiftable into or out of the notches, of means for locking the lever from 20 movement including an arm, an abutment disposed in spaced relation to the lever, an obstructing member carried on the arm and shiftable with the arm into a position 25 against said abutment and in the path of movement of the lever to its operative position, and key actuated means for oscillating the arm to carry the obstructing member out of its obstructing position, said obstructing member being loosely mounted for independent limited shifting movement upon 30 said arm.

6. The combination with a switch stand having a notched table and a swinging operating lever shiftable into or out of the 35 notches, of means for locking the lever from movement including an arm, an abutment disposed in spaced relation to the lever, an annular obstructing member carried upon said arm and in a plane parallel to the plane 40 of the obstructing member into a position against said abutment and in the path of movement of the lever to its operative position, and key actuated means for oscillating the arm to carry the obstructing member out 45 of its obstructing position.

7. The combination with an operating member movable into or out of an inoperative position, of means for preventing movement of the member from its inoperative position including a rigid abutment disposed 50 in spaced relation to the operating member when in its inoperative position, a key actuated oscillatable arm, and an obstructing member loosely carried by said arm and 55 shiftable thereby into a locking position in the path of movement of the lever and between the operating member and said abutment, the obstructing member being loosely mounted upon said arm to permit the obstructing member to sustain shock without 60 transmitting it to the key actuated mechanism.

8. The combination with a switch stand having a notched table, a blockhead mounted 65 on the table for rotary movement, a lever

hinged to the extremity of the blockhead for movement into or out of such notches, said lever having an extension at right angles to the lever, a housing mounted upon the blockhead above the pivotal axis of the lever, an 70 obstructing member disposed within the housing and movable into position behind said extension of the lever and in this position preventing the lever from shifting to a horizontal position out of said notches, 75 a weight operatively engaging said obstructing member and preventing its movement from behind the extension of the lever, key actuated means for first lifting said weight out of its locking position and then shifting 80 said obstructing member out of its obstructing position or shifting the obstructing member to its obstructing position and then lowering the weight to its locking position, and means for preventing the return of the 85 key to a position where it may be removed until said obstructing member has been shifted to its obstructing position.

9. The combination with a switch stand having a notched table, a blockhead mounted 90 upon the table, an operating lever pivoted upon the table for vertical movement and shiftable into or out of said notches, of means for holding the lever in a vertical position and in engagement with one of said 95 notches including a housing mounted upon the blockhead above the pivotal axis of the lever and having a keyhole, an obstructing member oscillatably mounted within the housing and normally disposed in the path 100 of movement of the lever, an abutment forming part of the housing and against which said obstructing member bears when in its obstructing position, said obstructing member moving away from the abutment 105 when shifted out of its obstructing position, a weight disposed within the housing and normally locking the obstructing member from movement away from its obstructing position, a keyhole guard swingingly mounted upon the exterior of the housing and normally closing the keyhole and being yieldingly held in its closing position by said weight, a movement of the keyhole guard to uncover the keyhole acting to partially lift 110 the weight and thereby almost release the obstructing member, and a rotatable key actuated member disposed within the housing and adapted when rotated by the key to first 115 engage the weight to entirely free it from its engagement with the obstructing member and then acting to oscillate the obstructing member from its obstructing position.

10. The combination with a switch stand having a notched table, a blockhead mounted 120 thereon for swinging movement, a lever pivoted to the blockhead for pivotal movement and normally disposed in one of said notches, of means preventing the lever from 125 being shifted out of one of said notches in- 130

- cluding an abutment, an obstructing member shiftable into or out of a position between said lever and the abutment and when in such position preventing movement of the lever, and key actuated means for shifting said obstructing member into or out of its obstructing position, the key actuated means and the obstructing member being so constructed as to permit the obstructing member 5 to sustain shocks without transmitting them to the key actuated mechanism.
11. A switch stand lock including a housing adapted to be applied to a switch stand and having a keyhole, the under face of the 15 housing being open to permit the movement of the switch stand lever therethrough, and key actuated mechanism mounted within the housing and including a switch lever locking member normally disposed in a locking 20 position but adapted to be shifted to a raised position, a key actuated member disposed within the housing behind said keyhole and having spaced lugs adapted to operatively engage the switch lever locking member 25 and shift it, the lugs being spaced a sufficient distance apart to permit a limited rotative movement of the key actuated member relative to the switch lever locking member, means normally locking the switch lever locking member from movement away 30 from its locking position, and means carried by the key actuated member contacting with said last named locking member and shifting it from its locking position before 35 one of said lugs operatively engages said first named locking member to retract it.
12. The combination with a switch stand having a notched table, a blockhead mounted thereon for oscillation, an operating lever 40 pivoted to the blockhead and having an extension beyond the pivotal axis of the lever, said lever being engageable in the notches when depressed, of means for preventing the lever being raised from the notches includ- 45 ing a housing mounted upon the blockhead and having a keyhole, an arm pivotally mounted for swinging movement within the housing, an obstructing member carried by the arm and normally disposed in a position 50 operatively bearing against one wall of the housing and in the path of movement of the lever as it moves to its horizontal position, and key actuated means within the housing for oscillating said arm to carry said ob- 55 structing member out of the path of movement of the lever.
13. The combination with a switch stand having a notched table, a blockhead mounted thereon for oscillation, an operating lever 60 pivoted to the blockhead and having an extension beyond the pivotal axis of the lever, said lever being engageable in the notches when depressed, of means for preventing the lever being raised from the 65 notches including a housing mounted upon
- the blockhead and having a keyhole, an arm pivotally mounted for swinging movement within the housing, an obstructing member carried by the arm and normally disposed in a position operatively bearing against one 70 wall of the housing and in the path of movement of the lever as it moves to its horizontal position, means for locking the arm with the member in its obstructing position, and key actuated means for unlocking said locking means and then upon a further rotation of the key carrying the arm and the obstructing member out of its obstructing position.
14. The combination with a switch stand 75 having a notched table, a blockhead oscillatably mounted thereon and a swinging operating lever shiftable into or out of the notches, of means preventing movement of the lever out of the notches comprising an oscillatable key actuated arm, an annular obstructing member loosely supported upon said arm, and an abutment against which the annular member bears at one point, the arm being normally in a position where the annular member is disposed in the path of movement of the lever and between said lever and the abutment.
15. In a switch lock, a housing having a keyhole, locking mechanism within the housing, a shield pivoted upon the housing on the outer face thereof but normally closing said keyhole, a weight resisting movement of the locking mechanism and operatively connected to said shield to urge it to a closed position over the keyhole, said operative connections causing the lifting of the weight from a position releasing the locking mechanism when the shield is shifted to uncover the keyhole.
16. In a switch lock, a housing having a keyhole, a shield pivoted upon the outer face of the housing and normally disposed over the keyhole, a locking mechanism disposed within the housing, a weight disposed within the housing and having a shoulder normally engaging the locking mechanism to prevent any actuation thereof, and an operative connection between the shield and said weight whereby a shifting of the shield in one direction will lift the weight and a release of the shield will release the weight and cause the weight to shift the shield to its closed position.
17. In a lock of the character described, a housing having a keyhole, a shield pivotally mounted upon the outer face of the housing and normally disposed over said keyhole, key actuated locking mechanism disposed within the housing, a weight disposed within the housing and having a shoulder normally locking said key actuated mechanism from actuation, and an operative connection between the shield and weight whereby a shifting of the shield in a direction to dis- 120
- 125
- 130

close the keyhole raises the weight, said weight urging the shield to its closed position, a rotation of the key actuated mechanism under the action of the key inserted in 5 the keyhole causing the further lifting of the weight entirely out of its locking position.

18. The combination with a member pivoted for oscillation, of means for preventing the 10 oscillation of said member comprising a housing disposed over the path of movement of said member, the housing having a key hole and an inwardly extending abutment, a key actuated arm disposed within the housing, 15 an obstructing member carried upon said arm and movable into or out of engagement with said abutment, said obstructing member when it is in its normal position being disposed in the path of movement of the pivoted member and between the pivoted member and the abutment, and key actuated means for shifting said obstructing member 20 out of its position in said path of movement and out of its abutment engaging position. 25 19. In a lock of the character described, a housing having a keyhole, a spindle within the housing extending in line with the keyhole, an arm oscillatably mounted on the spindle and carrying an obstructing member, a head mounted to rotate with said arm and having a detent face at one end and a laterally projecting lug at the other end, a locking weight having a detent face normally engaging with the first named detent 30 face and resisting any movement thereof, and a key actuated member mounted on said spindle and having means for engaging said weight and lifting it from its engagement with the face on said head and having means 35 to engage the lug on said head to thereby rotate the head and arm and shift the obstructing member from its obstructing position. 40

20. The combination with a switch stand 45 having a notched table, a blockhead oscillatably mounted thereon and an operating lever pivoted to the blockhead for movement into or out of said notches, said lever extending beyond its pivotal axis, of a housing 50 mounted on the blockhead and extending over the path of movement of the extension of the lever, the rear end of the housing having an abutment projecting toward the lever and one face of the housing having a keyhole, a key spindle projecting from one wall of the 55 housing toward the keyhole and in alinement therewith, a tubular shaft mounted upon the key spindle and having an arm at one end and a sector-shaped head at the 60 other, the outer end of the arm carrying a substantially elliptical head, the sector-shaped head being formed to provide a detent face at one end and at the other having a laterally projecting arcuate lug, an annular 65 obstructing member carried upon the

elliptical head and movable with it into or out of a position against said abutment and said spindle and between the abutment and the extension of the lever when the lever is disposed within the notch, a curved weight 70 pivoted at one end within the housing and having a detent face normally engaging with the detent face on the sector-shaped head to prevent a rotation of said tubular shaft, and a member mounted upon the 75 spindle for rotation therearound having an arcuate concentrically extending arm adapted when the member is rotated to engage said weight and lift it out of engagement with the sector-shaped head and having a lug engageable with the arcuate lug on the head, the arcuate arm on said member being disposed in a plane outward of the lug, and a key insertible 80 through the keyhole and adapted to engage the end of the arcuate arm to thereby turn the head, the tubular shaft, the arm, and the obstructing member. 85

21. The combination with a switch stand having a notched table, a blockhead oscillatably mounted thereon and an operating lever pivoted to the blockhead for movement into or out of said notches, said lever extending beyond its pivotal axis, of a housing mounted on the blockhead and extending 90 over the path of movement of the extension of the lever, the rear end of the housing having an abutment projecting toward the lever and one face of the housing having a keyhole, a key spindle projecting from one wall of the housing toward the keyhole and in alinement therewith, a tubular shaft mounted upon the key spindle and having an arm at one end and a sector-shaped head at the other, the outer end of the arm carrying a substantially elliptical head, the sector-shaped head being formed to provide a detent face at one end and at the other having a laterally projecting arcuate lug, an annular 95 obstructing member carried upon the elliptical head and movable with it into or out of a position against said abutment and said spindle and between the abutment and the extension of the lever when the lever is disposed within the notch, a curved weight pivoted at one end within the housing and having a detent face normally engaging with the detent face on the sector-shaped head to prevent a rotation of said tubular shaft, a member mounted upon the spindle 100 for rotation therearound having an arcuate concentrically extending arm adapted when the member is rotated to engage said weight and lift it out of engagement with the sector-shaped head and having a lug engageable with the arcuate lug on the head, the arcuate arm on said member being disposed in a plane outward of the lug, a key insertible 105 through the keyhole and adapted to engage the end of the arcuate arm to thereby turn 110

the member and shift the head, the tubular shaft, the arm, and the obstructing member, a shield pivoted upon the keyhole face of the housing on the exterior thereof and having an inwardly extending pin, the housing being slotted to permit the passage of the pin, said weight having a nose normally bearing upon the pin to urge the shield into a position over the keyhole, a rotation of the shield acting to partly lift the weight.

22. A switch stand lock comprising a housing having a keyhole, an oscillatable arm mounted within the housing and carrying a locking member, said arm having a shoulder, a weight having a shoulder normally engaging the first named shoulder and preventing said arm from oscillating to an unlocking position, a key actuated member rotatably mounted opposite the keyhole and having limited oscillative movement relative to the arm, and means carried by said member engaging the weight upon a rotation of the member in one direction to thereby carry the weight away from the shoulder on the arm

and permit the retraction of said locking member.

23. A switch stand lock, a housing having a keyhole, a swinging keyhole shield coacting therewith, an oscillatable arm mounted within the housing and carrying a locking member, a weight pivotally mounted within the housing and operatively engaging the keyhole shield to yieldingly urge it to its closed position, said weight having means locking the arm from oscillation in a direction to retract the locking member, an oscillatably mounted key actuated member disposed immediately opposite the keyhole, and means on said member for engaging said weight upon an oscillation of the member in one direction to thereby entirely raise the weight and shift it out of its locking engagement with the arm, and means on said member for disengaging said arm to cause the retraction of the locking member.

In testimony whereof I hereunto affix my signature.

NOAH J. BECKNER.
